DESIGN FOR A SALTCELLAR OR SIMILAR CONTAINER

Harry C. Gessler, Brooklyn, N. Y.

Application March 11, 1940, Serial No. 90,827

Term of patent 7 years

To all whom it may concern:

Be it known that I, Harry C. Gessler, a citizen of the United States and resident of New York city (Borough of Brooklyn), in the county of Kings and State of New York, have invented a new, original, and ornamental Design for a Saltcellar or Similar Container, of which the following is a specification, reference being had to the accompanying drawing, forming a part thereof, and of which Figure 1 is a view in side elevation of a saltcellar or similar container showing my new design, and Fig. 2 is a top plan view thereof.

I claim:

The ornamental design for a saltcellar or similar container, substantially as shown.

HARRY C. GESSLER.
